UNITED STATES PATENT OFFICE.

FRIDOLIN SCHIMMEL, OF FARIBAULT, MINNESOTA.

COMBINED TABLE AND WRITING-DESK.

1,369,195.

Specification of Letters Patent. Patented, Feb. 22, 1921.

Application filed May 19, 1919. Serial No. 293,072.

To all whom it may concern:

Be it known that I, FRIDOLIN SCHIMMEL, a citizen of the United States, residing at Faribault, in the county of Rice and State 5 of Minnesota, have invented certain new and useful Improvements in Combined Tables and Writing-Desks; and I do hereby declare the following to be a full, clear, and exact description of the invention, such 10 as will enable others skilled in the art to which it appertains to make and use the same.

My invention has for its object to provide an improved combination table and writing 15 desk; and to such ends, generally stated, the invention consists of the novel devices and combinations of devices hereinafter described and defined in the claim.

This improved combination table comprises a table proper having a large main 20 drawer provided with supplemental drawers slideable into and out of the ends thereof. The main drawer is provided with a flat top surface that affords a supplemental table 25 top or writing desk board. The supplemental drawers are slideable in the main drawer under the supplemental table top, and when forced or moved to innermost positions, permit the main drawer to be moved 30 like an ordinary drawer, to and from positions under the top of the main table. The invention also involves minor but important features, as will presently appear.

In the accompanying drawings which 35 illustrate the invention, like characters indicate like parts throughout the several views.

Referring to the drawings:—

Figure 1 is a front elevation of the combination table, some parts being sectioned; 40 Fig. 2 is a plan view showing the main and supplemental drawers drawn out;

Fig. 3 is a bottom plan view of the table showing the main and supplemental drawers in closed positions; and

Fig. 4 is a section on the line 4—4 of Fig. 2.

The main table comprises a top board 5, a rectangular marginal frame 6 supporting the top board 5, and legs 7 supporting the 50 frame 6 in the usual or any suitable way.

In the drawings, the legs 7 are shown as very short, but it will, of course, be understood that they may be made of any desired length.

55 The main drawer is indicated by the nu-

meral 8, and the supplemental drawers by the numeral 9. The main drawer is formed with openings, but at its ends, is provided with rabbeted guide bars 10 that slide on rail flanges 11 secured to and projecting inward from the ends of a table frame 6. The bars 10 project rearward of the back of the drawer 8 and their ends are tied together by a cross bar 12, the ends of which underlap the rail flanges 11 and thus hold the 60 main drawer against vertical wobbling movement while free for sliding movement. The outward movement of the drawer 8 is limited by engagement of its cross bar 12 with another cross bar 13 located immediately below the guide bars 10 with its ends secured to the rail flanges 11. 65

On the level with the upper edge of its front board, the main drawer 8 is provided with a supplemental top board or writing 70 board 14 that is located immediately below the plane of the bottom of the table top 5 so that it is free to slide under the same. This board 14, at its front and rear edges, respectively, is rigidly secured to the front 75 and back boards of the main drawer 8. In a direction transversely of the main drawer or longitudinally of the table, the board 14 terminates considerably short of the ends of the said top board 5. 80

The supplemental drawers 9 slide directly over the tops of the guide bars 10 of the main drawer and are further guided by supporting rails or cleats 15 and 16 secured, respectively, to the front and back boards of 85 the main drawer 8. The supplemental drawers are of such length that both thereof can be slid inward to positions in which their extreme outer ends will be flush with, or inside of the ends of the main drawer, so 90 that when forced to closed position, they may be freely moved with the main drawer to closed position shown in Fig. 3. The extreme inward movements of the two supplemental drawers are preferably limited by a 95 stop strip 17 secured to the front board of the main drawer. (See Fig. 3.)

It is important to note (see Figs. 2 and 4) that the main drawer can be drawn out to a position in which the supplemental 100 drawers will clear the front corner portions of the table frame 6. When the supplemental drawers are drawn out, as shown in Figs. 2 and 4, they lock the main drawer so that it cannot be accidentally pushed in. 110

ward, and thus hold the same in a position in which the writing board 14 will be exposed for use.

The supplemental drawers are formed 5 with various different compartments 9^a and 9^b for containing various different articles, such as generally used in writing letters, such as writing paper, envelopes, inkwells, and the like, and which will be exposed for the 10 use of a person using the writing board 14.

To prevent the supplemental drawers from being accidentally pulled out of the main drawer, the former are shown as provided with stop blocks 18 that will engage 15 the guide bars 10 when the supplemental drawers are drawn outward to positions shown in Figs. 2 and 4. Attention is here called to the fact that when the drawers 9 are drawn out, as stated, with their stops 20 18 engaged with the bars 10, the said drawers may, nevertheless be raised upward at their outer ends so as to carry the stops 18 over the bars 10, and thereby to permit the supplemental drawers to be entirely re- 25 moved with the least possible effort, for the purpose of cleaning the same, for example. This removing action is made possible by the fact that the writing board 14 terminates a considerable distance inward of the bars 30 10 and that there is no other device for holding the drawers down at a time when the inner ends of the supplemental drawers are immediately under the side edges of the said board 14.

35 This improved combined table and writing desk has, in practice, been found a very convenient article. The main table top 5 may be used as an ordinary table to support various different articles, such as a lamp, books, 40 and the like, and these need not be removed by persons desiring to use the device as a writing desk, for all one has to do is to draw out the main drawer and thereby expose the

writing board or table for such use, with the drawers containing the various articles de- 45 sired closely and conveniently located. Attention is further called to the fact that providing the main drawer, with the writing board 14, does not reduce the holding capacity thereof, since the two supplemental 50 drawers have a holding capacity equal to that that could be given to the main drawer if the latter were made in the usual way.

What I claim is:

The combination with a main table hav- 55 ing drawer guiding flanges at its ends, of a main drawer having guide bars slidable on said guide flanges and extended rear- 60 ward of the inner portions of said main drawer, said main drawer being open at its 65 ends and having a supplemental top board that terminates short of its sides, leaving portions of said supplemental drawers un- 70 covered by said supplemental board, supple- 75 mental drawers mounted to slide in said main drawer below the supplemental board there- 80 of, a cross bar connecting the front end portions of the end guide flanges of said main table, a cross bar connecting the inner ends of the guide bars of said main drawer 70 and engageable with the first noted cross bar to limit the outward movement of said main drawer to positions in which said sup- 75 plemental drawers may be drawn out, a stop on the main drawer for limiting the inward movement of said supplemental drawers, and stops on said supplemental drawers en- 80 gageable with the guide bars of said main drawer to limit the outward movements of said supplemental drawers.

In testimony whereof I affix my signature in presence of two witnesses.

FRIDOLIN SCHIMMEL.
